Primary Examiner — Leanne Was-Englehart

(57) **CLAIM**

The ornamental design for a "lighting fixture," as shown and described.

DESCRIPTION

FIG. 1 is a front perspective view of a light fixture;
FIG. 2 is a back perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom plan view thereof;
FIG. 9 is a front perspective view thereof;
FIG. 10 is a back perspective view thereof;
FIG. 11 is a front elevational view thereof;
FIG. 12 is a rear elevational view thereof;
FIG. 13 is a right side elevational view thereof;
FIG. 14 is a left side elevational view thereof;
FIG. 15 is a top plan view thereof; and,
FIG. 16 is a bottom plan view thereof.

The broken lines in the drawings illustrate portions of the lighting fixture that form not part of the claimed design.
